UNITED STATES PATENT OFFICE.

CHARLES GOLDSTEIN, OF CHICAGO, ILLINOIS, ASSIGNOR TO PHILIP V. SPINNER.

LOOSE-LEAF BINDER.

1,401,250.

Specification of Letters Patent. Patented Dec. 27, 1921.

Application filed October 29, 1920. Serial No. 420,343.

To all whom it may concern:

Be it known that I, CHARLES GOLDSTEIN, a citizen of the United States, and a resident of Chicago, in the county of Cook and State 5 of Illinois, have invented certain new and useful Improvements in Loose-Leaf Binders, of which the following is a specification.

This invention relates to improvements in loose-leaf binders, and more particularly to 10 binders used for removably securing sheets or leaves of paper, and although the invention is applicable for many purposes, its use in connection with sample books, photograph binders, and the like, suggests itself as particularly desirable.

The object of the invention is to provide 20 a simple and inexpensive article of the character described, and one which is calculated to be especially tenacious in its binding qualities, and readily manipulated in the removal or insertion of sheets. The novel features of the invention will presently be set forth in detail with reference to the accompanying drawings, in which the device is 25 clearly illustrated by a series of figures which may be briefly described as follows:

Figure 1 is a perspective view of the binder, showing the novel features of construction and manner of binding,

30 Fig. 2 is a cross-sectional view taken on line 2—2 of Fig. 1,

Fig. 3 is a longitudinal view in section taken on line 3—3 of Fig. 1, and

Fig. 4 is an enlarged view in perspective of 35 a portion of the binder.

A loose-leaf binder as commercially known, is in reality a book wherein the covers are separable from the contents or leaves, thereby enabling the latter to be 40 arranged, removed, or otherwise inserted at will. Manifestly, different types and kinds of fastening means are employed to connect the covers and sheets together along one edge, these fastening means being removed 45 or unfastened when the cover and sheets are to be removed.

As herein illustrated, the binder embodying the invention comprises two covers, a bottom cover 1 and a top cover 2, made of 50 comparatively stiff material, such as is ordinarily used in the book binding art, and between which are held the sheets 3 to be bound. The bottom cover is preferably stiff or relatively non-flexible throughout, where- 55 as the top cover is hinged or made partially flexible along a line spaced inwardly from

and extending parallel to the back or bound edge as at 4, thus permitting the turning back of the top cover in opening the binder.

Referring more in detail to the structure 60 of the covers, the same are provided along corresponding edges with stiff binding rails 5 and 6. The rail 5 of the bottom cover preferably comprises a strip 7 of relatively 65 stiff material such as wood, which forms the backbone of the rail, so to speak, there being formed in the outwardly facing surface and located midway between the edges, a longitudinal channel 8. Extending over the channel 70 and along the outer or under side of the rail 7 is a thin strip of wood 9 or cardboard, which transforms the channel into a closed passage extending through the rail. A layer 75 of binding cloth 10 envelops the strips 7 and 8, as well as the entire surface of the 80 cover.

The upper cover 6 is made in a somewhat similar manner, having as its foundation a relatively stiff strip of wood 11, or the like, having an upwardly facing channel 12 along 85 its top face, this channel being retained after the covering layer 13 is applied.

The passage in the rail 5 and channel in the rail 6 occupy corresponding positions, and co-operate with a binding member or 85 strap 14 to bind the covers and contents together. The strap 14 may be of any suitable material, either endless and elastic, or a non-elastic strap with buckle connection as disclosed in the preferred form. The 90 strap 14 is threaded through the passage in the lower binding rail 5, and free to slide endwise therein, the end portions passing around the ends of the upper rail 6, and along the channel therein, the thickness of 95 the strap and the depth of the channel being approximately equal so that the former will be flush therein. A buckle 15 of the friction type is secured at one end of the strap so that by pulling on the free end of 100 the strap the same may be drawn tight and the rails forced toward each other, thus binding the edges of the sheets securely between them.

A buckle made in this manner provides a 105 very secure and simple device which is readily and easily manipulated in removing or inserting the sheets. The stiff binding rails exert an even pressure throughout their entire length; thus the sheets are uniformly 110 and adequately retained by tightening the strap to a moderate and non-excessive de-

gree of tautness. It provides an exceedingly handy and convenient binder where frequent removals or separation of the sheets is desired, as, for instance, in binding sample cards, or samples of fabrics and the like.

Having described a preferred embodiment of my invention, what I claim as new and novel is as follows:

10. I claim as my invention:

1. A loose leaf binder comprising a binding strap, and cover members adapted to retain loose sheets therebetween, one of said cover members having a channel-like groove 15 extending adjacent one edge thereof and adapted to receive the strap, and the other cover member being provided, adjacent one edge thereof, with a passage adapted to confine the strap.

20. 2. A loose-leaf binder comprising, in combination, relatively stiff cover members adapted to retain loose sheets therebetween, one of said covers being provided with a channel-like groove adjacent one edge there-

of, the other cover being provided adjacent 25 an edge, with a passage extending through the body portion thereof, and open at its ends only, and a binding element extending through said passage in one cover, and lying in the groove of the other cover, and 30 having its ends connected, substantially as described.

3. A loose leaf binder comprising, in combination, relatively stiff cover members adapted to retain loose sheets therebetween, 35 one of said covers being provided with a groove adjacent one edge, the other cover being provided with a passage extending through the body portion and open at its ends only, said passage being of the same 40 width as said groove, and a binding element extending through and fitting said passage, and lying in said groove, and having its ends connected, substantially as described.

In witness whereof I hereunto subscribe 45 my name this 25th day of October, A. D. 1920.

CHARLES GOLDSTEIN.
